UNITED STATES PATENT OFFICE.

JONATHAN R. NAYLOR, OF THREE RIVERS, MICHIGAN, ASSIGNOR OF ONE-FOURTH TO ALFRED E. NAYLOR, OF THREE RIVERS, MICHIGAN.

COMBINED SPIKE AND SPRING TOOTH HARROW.

No. 799,399.

Specification of Letters Patent.

Patented Sept. 12, 1905.

Application filed December 27, 1904. Serial No. 238,513.

To all whom it may concern:

Be it known that I, JONATHAN R. NAYLOR, a citizen of the United States, and a resident of Three Rivers, in the county of St. Joseph, State of Michigan, have invented a new and useful Combined Spike and Spring Tooth Harrow, of which the following is a specification.

This invention relates to combined spike and spring tooth harrows, in which harrows can be used one style of teeth at a time or both style of teeth at a time, as desired, and the invention especially relates to a harrow of this class patented to me in the United States May 30, 1899, No. 625,793.

The object of the invention is to produce a more possible and convenient plan of adjusting a set of spike-teeth and a set of spring-teeth in their relation to each other in producing certain actions on the soil and in throwing the sets of the teeth out of the soil.

In the accompanying drawings, forming a part of this specification, Figure 1 is a plan of one section of a harrow, parts being broken away; Fig. 2, a side elevation looking from a point at the right of Fig. 1; Fig. 3, an enlarged plan of a front corner attachment of the harrow-frame; Fig. 4, an enlarged view looking from a point at the left of Fig. 3; Fig. 5, an enlarged side elevation of a rear corner attachment of the harrow-frame looking from a point at the left of the right-hand side or from a point at the right of the left-hand side of the harrow-frame; Fig. 6, an enlarged end elevation looking from a point at the right of Fig. 5 and showing a broken tooth-bar attached; Fig. 7, an enlarged elevation of one of the tooth-bar double supports looking from a point either at the left of the right-hand side of the frame or at the right of the left-hand side of the frame; Fig. 8, an enlarged section near dotted line *c c* in Fig. 1 looking from a point at the right, parts being broken away; Fig. 9, a plan of enlarged broken parts from the right-hand central portion of Fig. 1, and Fig. 10 is an elevation looking from a point below Fig. 9.

Referring to the parts of the drawings pointed out by numerals, 12 represents the spring-tooth bars bearing spring-teeth 16, alternating with spike-tooth bars 13, bearing spike-teeth 15. These tooth-bars are made of tubular metal. Taking three of each style tooth-bars and beginning at the front with a

spring-tooth bar 12, we would end at the rear 55 with a spike-tooth bar 13, as in my former patent above referred to. By this means the last action on the soil was by spring-teeth, leaving a field in rough and uneven condition and frequently leaving furrows which storms 60 would gully out and wash the soil away. I overcome this by the addition of the fourth spike-tooth bar 20, bearing spike-teeth 15, the action of which is in the rear of any action by spring-teeth 16, leaving the soil in a fine 65 smooth cultivated condition.

One section of the harrow-frame is here shown; but two like sections are usually employed and attached to the draft-rod 17, to which whiffletrees are to be attached in the 70 usual manner. The draft-rod 17 is here shown broken away at the right-hand end.

In making the frame-sections pipe-like rods 18 at the sides, 19 at the front, and 20 at the rear are used. The rods at the front corners are held firmly together by the elbow concaves 42, one above and one below and clamped together by bolts, as 21, Fig. 4. On the interior of the upper concave 42, Fig. 4, is a nib 43, which is to fit a hole in the rods 18 80 and 19 to prevent them from working loose or pulling out. The rear bar or rod 20 serves the purpose of a rear tooth-bar, as well as a rod of the frame-section at the rear. To secure the rear corners, I employ the single-tooth-bar 85 supports 22. They are provided with horizontal concaves 23, Fig. 6, to receive the rear ends of the side rods 18. These tooth-bar supports 22 are bolted at 24 to the under side 90 of the rods 18, and below this the supports 95 are provided with a double wall or an inner wall 25 and an outer wall 26, parallel therewith, and with a space 27 between, Fig. 6. In the inner wall 25 is a hole 28, Fig. 5, to receive the end of the tooth-bar 20 in a manner to turn or partially revolve therein, Fig. 6, said tooth-bar 20 being broken away in said figure. The inner walls 25 form the support to the ends of the tooth-bar 20, the outer wall 26 prevents the tooth-bar from working 100 too far endwise, and the space 27 provides for passing the hand in and inserting the spring-keys 29 into holes in the ends of the tooth-bars to prevent the latter from drawing out of the holes 28.

The tooth-bar double supports 30 at the sides of the frame-sections for the tooth-bars 12 and 13 are the same as the supports 22 for

the tooth-bar 20 except they are double, as in Fig. 7, one serving at the ends of two bars 12 and 13, as in Fig. 1. Like spring-keys 29 are used in the ends of these tooth-bars 12 and 13 and serve the additional purpose of preventing the side rods 18 from springing out sidewise. Like concaves fit on the under side of rods 18, and the supports 30 are bolted to the rods 18 at 31.

- 10 The tooth-bars 12, 13, and 20 have bearings in a central support 50, beneath the bar 35, Figs. 1, 8, 9, and 10. Each spring-tooth-bar 12 has an upwardly-extended arm 32, and their upper ends are pivotally attached to a bar 33.
- 15 Each spike-tooth bar 13 has an upwardly-extended arm 34, the upper ends of which are pivotally attached to a bar 35, Figs. 1, 8, 9, and 10.

An ordinary lifting-lever 36 and rack 47 are shown in Figs. 1 and 8, it being attached to the arm of the spike-tooth bar 20 at the rear, and when swung forward the spike-teeth 15 are thrown out of the soil.

By means of a connection of one of the 25 spring-tooth bars 12 with a spike-tooth bar 13 the spring-teeth 16 are thrown out of the soil at the same time the spike-teeth are thrown in the soil. I make this connection at a single point by means of what I term a "toothed" 30 connection, consisting of teeth 44 on the hub of the spike-tooth arm 34 and a short arm 41, having a hub loose on a contiguous spring-tooth bar 12, said hub being provided with teeth 37, meshing with the teeth 44 of the 35 spike-tooth arm 34. The spring-tooth arm 32, opposite the short arm 41, is provided with an arcuate way 39, and the short arm 41 has a lug 45, Figs. 1, 9, and 10, inserted through said way 39 and held secure by a thumb-nut 40. When thus held, a swing of the lifting-lever 36 in either direction forward or back 40 partly rotates the tooth-bars 12, 13, and 20 in one direction or the other in unison. By means of bars 33 35, arms 32 34, and this 45 simple toothed connection at a single point the action of the lifting-lever 36 first on the spike-tooth bars 13 is very easy, whereas in my old patent above referred to, where the

action was first on the spring-tooth bars and wherein sets of all the tooth-bars were geared together, the operation of raising the sets of teeth was very difficult and sometimes impossible.

When desiring to adjust the spring-teeth 16 in their relation to the spike-teeth 15 with 55 reference to their specific action in the soil or their non-action, I simply loosen the thumb-nut 40, which frees all the spring-tooth bars 12, since the hub of the short arm 41 is loose on its tooth-bar, when by raising or bearing 60 on one style of teeth all of that kind are set farther in or out of the soil.

Having thus described my invention, what I claim as new, and desire to secure by Letters Patent of the United States of America, is— 65

1. A harrow having a set of revoluble tooth-bars bearing spike-teeth, and a set of revoluble tooth-bars bearing spring-teeth, provided with upwardly-projecting arms, a bar pivotally attached to the upper ends of the arms of each set, a lifting-lever attached to the bar of the spike-tooth set, an arm of one spring-tooth bar being provided with an arcuate way, a short arm having a hub loose on said tooth-bar and by the side of the way and having a lug passed through the way, a thumb-nut on the lug, and a toothed connection between the hubs of the short arm and the contiguous spike-tooth arm, substantially as set forth. 80

2. A harrow having different sets of revoluble tooth-bars provided with upwardly-projecting arms, a bar pivotally attached to the upper ends of the arms of each set, a lifting-lever attached to one set, an arm of a tooth-bar 85 of another set provided with an arcuate way, a short arm by the side of said way loose on the tooth-bar and having a lug passed through the way, a thumb-nut on the lug, and a toothed connection between the hubs of the short arm 90 and the contiguous spike-tooth arm, substantially as set forth.

JONATHAN R. NAYLOR.
